UNITED STATES PATENT OFFICE.

GONZALO M. CLIVIO, OF NEW YORK, N. Y.

PROCESS AND APPARATUS FOR EXTRACTING NICOTINE AND OTHER OILS FROM TOBACCO SMOKE.

Application filed July 5, 1922. Serial No. 572,869.

This invention relates to a process for extracting nicotine and other oils from tobacco smoke and to means for accomplishing this result or carrying out the process.

5 One of the objects of the invention is to provide a process of the character described that may be used with cigarettes, cigars or pipes and by means of which any desired percentage of the nicotine or other oils may 10 be extracted from the tobacco smoke.

Another object of the invention is to provide means for extracting and collecting nicotine and other oils so constructed and arranged that the means may be easily removed 15 from a pipe, cigarette holder or cigar holder for cleaning.

Another object of the invention is to provide simple practical and effective means for extracting and collecting nicotine from tobacco smoke.

Further objects of the invention will appear from the following description taken in connection with the drawings which form a part of this application and in which,

25 Fig. 1 is a sectional elevation of a cigarette holder having one form of extracting device positioned therein.

Fig. 2 is an enlarged sectional elevation of the nicotine extracting device shown in Fig. 1.

30 Fig. 3 is a sectional elevation of another form of extracting and collecting means adapted for use with a cigarette or cigar holder.

35 Fig. 4 is an elevational view showing the tubular member used in the device illustrated in Fig. 3.

40 Fig. 5 is an enlarged sectional elevation of a portion of the extracting and collecting means shown in Fig. 3.

Fig. 6 is a sectional elevation showing another form of device for extracting and collecting nicotine and other oils from tobacco smoke and used in connection with a cigarette holder.

45 Figs. 7, 8 and 9 are enlarged sectional elevations of the parts of the device shown in Fig. 6.

Fig. 10 illustrates a form of extracting device used in connection with a pipe and

50 Figs. 11-15 inclusive are enlarged sectional elevations of the parts of the device shown in Fig. 10.

The invention may be briefly described as consisting of a process for extracting nicotine and other oils from tobacco smoke which consists of causing the smoke to move at a high velocity and to impinge against a condensing surface. Various forms of mechanical devices for carrying out this process have been illustrated but in each of these forms the smoke is caused to pass through constricted openings in a member disposed in the path of movement of the smoke and a condensing surface is disposed adjacent the member first mentioned and is spaced from the openings and positioned in the path of the smoke after the smoke has passed through the openings. In order to prevent the nicotine from reaching the end of the mouth piece means has also been provided for collecting the nicotine.

Referring to the drawings the device is shown in Figs. 1 and 2 in its simplest form and consists of a concaved or dished member 20 having a cylindrical or slightly tapered wall 21 and a curved end 22. This member as shown in Fig. 1 is placed in a cigarette holder 23 being held therein by friction and the member 20 is provided with a plurality of constricted openings 24 which as shown in Fig. 1 are spaced from the inner wall of the cigarette holder 23. When the smoke is drawn through the cigarette holder by the smoker it passes through the openings 24 and because of the constricted nature of these openings the smoke is caused to move at a high velocity and impinges against the inner wall of the cigarette holder 23 whereupon nicotine and other oils are condensed on the surface of the holder 23. The size of the openings 24 may be determined by experiment and is properly proportioned with respect to the distance from the openings to the inner wall of the cigarette holder. By changing the size of the openings and the distance from the inner wall of the holder 23 the amount of the oils deposited on the cigarette holder may be varied.

100 In Figs. 3, 4 and 5 another form of mechanical means for carrying out the process is illustrated. In this form of the device the cigarette holder is divided into a cigarette engaging tubular member 30 and a mouth piece 31. These members are con-

nected by an elongated tubular member 32 having a slightly flaring end 33 adapted to engage the tapered end 34 of the member 30. The elongated member 32 has one end 35 closed except for a plurality of constricted openings 36. The condensing surface 37 is positioned within the elongated member 32 and is slightly spaced from the openings 36. This member 37 is carried at one end of a spiral spring 38 and is spaced from the closed end 35 of the elongated member 32 by one end 39 of the spring 38 which passes through the member 37 and engages the closed end 35. The spiral spring 38 extends entirely through the elongated member 32 as clearly shown in Fig. 3. The spring 38 in addition to spacing the condensing member 37 from the openings 36 also serves to collect the condensed oils and to prevent their reaching the mouth piece 31. The elongated tubular member 32 also acts as an ejector since the member 30 may be moved along the member 32 when the cigarette has been smoked thereby engaging the end 35 with the cigarette and forcing the cigarette from the tapered end 34 of the member 30.

In Figs. 6, 7, 8 and 9 is illustrated another and the preferred form of the invention. In this form of the device a conical tubular member 40 is adapted to fit within the outer end of a cigarette holder 41 and the apex of this member is provided with a cover 42 having an opening 43 therethrough. A second conical member 44 having a closed end 45 is adapted to fit within the member 40 and the closed end has formed therein a plurality of constricted openings 46. As clearly shown in Fig. 6 the openings 46 are spaced from the inner wall of the member 40 and as the smoke is drawn through the cigarette holder it passes through the openings 46 and the nicotine and other oils are condensed on the inner surface of the member 40. The cover 42 of the member 40 serves to prevent the oils from passing into the cigarette holder 41 and to the mouth of the smoker.

Figs. 10-15 inclusive illustrate a form of device adapted for use with pipes. In this construction a cylindrical member 50 having one end 51 closed except for an opening 52 therethrough is positioned in the stem 53 of the pipe 54. A tubular member 55 having a laterally extending flange 56 intermediate its ends is positioned within the member 50 with the flange 56 abutting against a flange 57 formed on the member 50. The flange 57 in turn abuts against the end of the pipe stem 53. A cylindrical member 58 is positioned within the member 55 and has one end 59 closed except for constricted openings 60. A lining member 61 is mounted in the mouth piece 62 and the mouth piece and lining member are mounted on the other end 65 of the cylindrical member 55. As the smoke

is drawn through the pipe it will pass through the opening 52 and through the constricted openings 60 and the nicotine and other oils will be deposited on the spaced inner wall of the member 55.

From the foregoing specification it will be seen that a simple and effective process has been developed for removing the nicotine and other objectionable oils from tobacco smoke. It will be noted that the members 75 may be easily and quickly taken apart and cleaned thereby rendering the device capable of repeated use.

Although certain specific forms of the device for carrying out this process have been 80 illustrated and described, it will be understood that I do not wish to limit myself to any particular mechanical means and that the invention is capable of further modification. It will be evident therefore that other changes in the construction and arrangement of the various parts may be made without departing from the spirit or scope of the invention as expressed in the following 85 claims.

What I claim is:—

1. A process for extracting nicotine and other oils from tobacco smoke, which consists in accelerating the flow of smoke from an initial velocity and causing the smoke to 95 impinge fully against a condensing surface.

2. A process for extracting nicotine and other oils from tobacco smoke which consists of causing the smoke to flow at one velocity, then accelerating said flow by passing 100 the smoke through constricted openings and causing the smoke to impinge against a condensing surface when at its maximum velocity.

3. A device for extracting and collecting 105 nicotine and other oils from tobacco smoke comprising a tapered tubular member having its large end open and having an apertured cover at the smaller end thereof, and a second tapered member adapted to fit in 110 the open end of the first member and having a curved end at the smaller end thereof, said second member having constricted openings 115 therein disposed directly in the path of the smoke and in close proximity to the inner wall of the first member.

4. A device for extracting and collecting nicotine from tobacco smoke comprising a tapered tubular member and a second tapered member adapted to fit within the first 120 member and having its smaller end closed and provided with constricted openings, the smaller end of the second member being in close proximity to the inner wall of the first member, the openings being so proportioned 125 and so spaced from said inner wall that the smoke will pass through the constricted openings at a high velocity and will impinge on said inner wall.

5. A device for extracting nicotine and 130

other oils from tobacco smoke comprising a tubular member and a second member adapted to fit within said first member and having a closed end in close proximity to the inner wall of the first member, said closed end having constricted openings therein, the openings being so proportioned and so spaced from said inner wall that the smoke will pass through the constricted openings at a high velocity and will impinge on said inner wall.

6. A device for extracting nicotine and other oils comprising a tubular member, a tapered member disposed therein, and having constricted openings therein in close proximity to the inner wall of the tubular member, the openings being so proportioned and so spaced from said inner wall that the smoke will pass through the constricted

openings at a high velocity and will impinge on said inner wall.

7. A device for extracting and collecting nicotine from tobacco smoke comprising a tubular member and a second tapered member adapted to fit within the first member and having its smaller end closed and provided with constricted openings, the smaller end of the second member being in close proximity to the inner wall of the first member, the openings being so proportioned and so spaced from said inner wall that the smoke will pass through the constricted openings at a high velocity and will impinge on said inner wall.

In witness whereof, I have hereunto set my hand this 30th day of June, 1922.

GONZALO M. CLIVIO.
